RADIO SIGNALING SYSTEM

Application filed December 22, 1926. Serial No. 156,309.

This invention relates generally to radio signaling or other amplifying systems adapted to be energized from a source of alternating current.

5 In operating radio receiving sets from alternating current, difficulty is experienced not only in suppressing the alternating current ripple but also in obtaining an undistorted response when used for telephonic reception. Even though the transformers coupling together the amplifiers are designed to amplify uniformly over the entire voice range, the system will frequently distort the low tones and cause rumbling noises in the 10 loud speaker. I have found that much of this distortion is caused by interaction between the different amplifier stages through the common source of current supply. Former types of alternating current supply systems have also been expensive because of the 15 necessity of elaborate filters to minimize current fluctuations.

It is an object of this invention to devise a 20 radio signaling system for operation from alternating current in which interaction between the amplifier stages will be minimized.

It is a further object of this invention to 25 devise a novel means for supplying a negative potential to the grid of an amplifier tube which is being energized from a source of rectified alternating current.

It is another object of this invention to 30 minimize noises produced in alternating current radio signaling systems because of fluctuations in the wave form of the alternating current supply.

It is a further object of this invention to 35 reduce the cost of and simplify the construction of filters for rectified alternating current by utilizing the field inductance of a loud speaker or other translator as one element of the filter.

Further objects of this invention will appear from the following description in which 40 I have set forth the preferred embodiment of my invention. It is to be understood that the claims are to be accorded a range of electrical equivalents consistent with the state of the prior art.

45 Referring to the drawings:

Figure 1 is a circuit diagram illustrating a conventional form of radio receiving circuit which is adapted to be energized from a current supply system such as shown in Fig. 2.

Fig. 2 is a circuit diagram illustrating a 55 rectifier and filter circuit for energizing a radio signaling system.

Fig. 3 is a circuit diagram of a B battery 60 eliminator incorporating certain of the principles included in the system of Figs. 1 and 2.

Fig. 4 is a circuit diagram of a B battery 65 eliminator incorporating the field inductance of a loud speaker as one element of a filter circuit.

The invention has been illustrated in the 70 drawing as being combined with a conventional form of radio receiving apparatus, although it is to be understood that certain features are applicable to a variety of systems employing electron emission relays. The 75 particular apparatus which I have shown comprises a plurality of electron relays coupled together in cascade so as to form a high frequency amplifier, a low frequency amplifier for actuating a translator or loud 80 speaker, and an intermediate detector, modulator or integrating device. Although any number of stages of amplification may be employed, the circuit has been simplified by showing only one stage of high or radio frequency amplification formed by the electron 85 relay 11. The output of the relay 11 is coupled to the input of the detector relay 12 while the output of the detector supplies one or more stages of low or audio frequency 90 amplifiers indicated diagrammatically at 13. The last stage of audio frequency amplification is preferably formed by a power amplifier relay 14, the output of which supplies a translator or loud speaker 15. These electron 95 relays are preferably of the three-element type comprising a grid or control element 17, electron emission element or filament 18, and plate or anode 19. As is well known in the art, the input circuit of each relay is connected across the grid 17 and electron emission element 18, while the output circuit is connected across the plate 19 and electron emission element. The first amplifier stage 100 is coupled to a suitable source of signal

is coupled to a suitable source of signal

energy such as an antenna 21 and ground 22, as by means of a tuned coupling transformer 23. The output of the electron relay 11 is similarly coupled to the input of detector tube 12 by means of a tuned radio frequency transformer 24, the output of the detector is coupled to the amplifier 13 by means of an audio frequency transformer 26, and the output of this amplifier coupled to the power amplifier stage 14 by means of audio frequency transformer 27.

The filaments of all of the relays with the exception of the power amplifier relay, are preferably connected in series relation across the bus conductors 101 and 102 which are adapted to be connected to a supply of direct current. The filament of the power amplifier 14 is preferably connected to a source of alternating current through bus conductors 103 and 104. The filaments of all the various electron relays are grounded to the negative B battery conductor 106. The outputs of the different electron relays are energized from a source of current which may be arranged to supply different potentials to the tubes depending upon their function. For example, the output of amplifier tube 11 and the outputs of the relays comprising amplifier 13, are shown as connected to a common anode potential bus conductor 107 which is adapted to supply a potential of say from 45 to 100 volts. For supplying current at a lower potential to the detector relay 12, the output of this relay is connected to the positive anode potential bus conductor 108. As the power amplifier 14 requires a relatively high anode potential, the output circuit of relay 14 is connected to the bus conductor 109. In order to maintain the proper negative bias upon the grids of the amplifier relays the potential drop across the series filaments may be employed or there may be provided a grid bias bus conductor 110 with which the inputs of amplifier relay 11 and the relays of amplifier 13 may be associated. A potentiometer 29 may be employed for varying the negative bias upon the grid of relay 11. As the power amplifier relay 14 requires a much higher negative grid bias a separate anode bus conductor 111 is associated with the input circuit of this relay.

While any standard form of loud speaker or translator may be employed, I preferably employ one having a wound field coil adapted to be energized from a source of direct current. Thus in the loud speaker indicated there is provided an exciting coil 31 connected in the output circuit of power amplifier relay 14, and a field coil 32 having a relatively high inductance. For a purpose later to be described one terminal of field coil 32 is connected to bus conductor 112 while the other terminal is connected to bus conductor 101.

In Fig. 2 there is shown a system adapted

to be connected to alternating current supply lines for the purpose of supply current to the various bus conductors of the apparatus described with reference to Fig. 1. This system includes a transformer 36 having its primary winding 37 connected to the alternating current power supply lines L_1 and L_2 , which may be ordinary 60 cycle 110 volt lighting circuit. This transformer is provided with a plurality of secondary windings for supplying alternating current at different voltages. Thus the secondary winding 38 serves as a source of anode potential and has its central tap 39 indirectly electrically connected with the negative bus conductor 206.

As it is desirable from the standpoint of efficiency to employ full wave rectification, each terminal of winding 38 is connected to one or more rectifier elements, the number of elements employed depending upon the amount of current required. These rectifier elements may be of any common type such as electrolytic, electrochemical, or electronic. In this particular system I have incorporated the use of electronic rectifiers having filamentary cathodes. For energizing the filaments of the rectifier elements the low voltage transformer windings 43 and 44 are provided.

The rectifier elements are arranged in two separate groups, one group for supplying the anode potential and the other group for supplying the current for energizing the filaments of the electron relays. For example, the elements 40 have their filaments connected to the wires 46 and 47 from the transformer winding 43 and form one group of rectifier elements for supplying the anode potential, while the other rectifier elements 41 have their filaments connected to wires 48 and 49 leading from the transformer winding 44 and form the other group of rectifier elements for supplying the filament current. A positive connection to the rectifier circuit is made through wire 51 which is tapped to an intermediate point of transformer winding 43. The corresponding negative wire 52 is connected to the central tap 39 of transformer winding 38 through the resistances 53 and 54 or other impedances having substantial values of resistance, these resistances being for a purpose later to be described. Interposed between the terminal wires 51 and 52 and the anode bus conductors are separate filter circuits 56 and 57. Filter circuit 56 for example may comprise a plurality of inductive elements or choke coils 58 connected in series relation, to the intermediate points of which are connected the shunt capacitances 59. The filter circuit 57, since it serves to supply the power amplifier, consists merely of a single choke or inductive element 61 and a capacitative element 62. While the filter circuits 56 and 57 have been

defined as being separate circuits, it is to be understood of course that certain filter elements may be common to both circuits; for example, a capacitative element 63 may be shunted across wires 51 and 52. The positive potential supplied to bus conductor 208 may be reduced by a resistance or other impedance 64 inserted between the conductors 207 and 208. Conductors 206 and 208 may be further shunted by capacitance 66 in order to utilize impedance 64 as a filter element.

The current for supplying the filaments of the electron relays is taken through wire 67 which is tapped in at an intermediate point of transformer winding 44, and wire 68 which is connected to intermediate tap 39 of winding 38 either directly thereto or in series with resistances 53 and 54. A suitable form 20 of filter circuit 69 is interposed between wires 67 and 68 and the bus conductors 202 and 212. One form of satisfactory filter comprises a resonant circuit 71 inserted in series with positive wire 67, this circuit comprising 25 a capacitance shunted across an inductance and being tuned to reject the second harmonic of the alternating current frequency, this harmonic being 120 cycles in case of a 60 cycle supply. The other parts of the 30 filter include inductive elements or chokes 72, between which are connected the shunt capacitances 73. A resonant circuit including inductance 74 and series capacitance 75 is shunted across wires 67 and 68 and tuned to 35 admit the second harmonic of the alternating current frequency. The filament bus conductor 201 is connected to the negative conductor 202 through series capacitance 76. Instead of supplying direct current to the 40 filament of the power amplifier relay, this filament is supplied with alternating current from the transformer winding 77, the terminals of which are connected to bus conductors 203 and 204. The central point 45 of transformer winding 77 is preferably grounded to wire 68 by means of wire 78.

To provide the necessary negative grid bias upon the amplifier relays, it has previously been the practice to either employ a separate 50 C battery or to utilize the potential drop across the relay filaments. Although this method may be satisfactory for the high frequency amplifiers and for the first stages of the low frequency amplifiers, it is impractical for the power amplifier relay since devices of this kind require a relatively high bias in excess of a potential drop across the relay filament. Furthermore, it is usually desirable as disclosed in the above system, to energize the filament of the power amplifier relay with alternating current because of its relatively heavy current consumption. To obviate the use of a large C battery, I have provided means for securing the necessary 60 negative potential from the rectifier circuit.

Thus a drop in potential is produced between the intermediate tap 39 of transformer winding 38 and either one or both of the negative conductors or filters 56 and 69 by inserting series resistances 53 and 54. The drop across resistance 54 is imposed upon bus conductor 210 while the combined drop across resistances 53 and 54 is imposed upon bus conductor 211. The impedance of these resistances may be sufficient to minimize the ripples of rectified alternating current as substantially no current flow will occur through conductors 210 or 211. However, additional filter means is preferably provided as by the use of resistance 79 inserted in series with conductor 211 and wire 39, and shunt capacitance 81. If desired, any or all of resistances 53, 54 and 79 may be replaced by choke coils. The use of a filter circuit between the source of grid bias potential and the input circuits of the relays is of value in minimizing distortion. It frequently happens that the power relay is loaded to capacity or even overloaded, so that at times the anode filter circuit must deliver a relatively heavy current. As 90 the potential drop across resistances 53 and 54 is dependent upon current flow, the bias upon the grid may be unduly disturbed, thus causing a distorted output. Distortion from this cause is most noticeable when amplifying voice currents of low frequency. However, by inserting the filter circuit described above these variations on the grid are minimized and the relay faithfully repeats input current modulations within a broad range of 95 loadings and frequencies.

Because of the cascade arrangement of the electron relays very slight fluctuations in the energizing current for the high frequency stages will cause greatly amplified noises in the loud speaker. Even if the rectified alternating current is completely filtered to minimize substantially all alternating current ripple, such interfering noises may still be produced by sudden fluctuations upon the alternating current supply lines due to the opening and closing of other circuits associated with the same. For example, with a radio receiving set installed in a dwelling, the operation of a lighting switch or a small motor from the same alternating current lines will cause sudden surges in the transformer 36, and as it is practically impossible to successfully filter out all of these surges after being rectified, interfering noises will be set 105 up in the loud speaker. As one feature of this invention I propose to minimize noises produced by sudden surges upon the alternating current lines by imposing a filter circuit between the supply lines and the transformer 36, the filter circuit being in proximity to the transformer. Thus as shown in Fig. 2, such a filter circuit may comprise series inductances or chokes 82 and shunt capacitances 83. By means of this filter sud-

den surges in the line at a point remote from the filter will not be transmitted to the secondary windings of the transformer.

In operating the above system, by virtue of the fact that field coil 32 of the loud speaker 15 is connected across bus conductors 201 and 212, this coil will be incorporated as one reactive element of the filter circuit 69. At the same time that the coil 32 is serving as a filter element, it is also being energized by the same source of current serving to energize the filament of the relay. By utilizing the field coil of the loud speaker in this manner, a less number of chokes may be employed in the filter circuit 69 with the result that the filter may be manufactured cheaper than has previously been possible. A decided advantage is obtained by supplying the output circuit of the power amplifier with current from a filter independent from the filter supplying the output of the other amplifier relay. When a single filter circuit is employed as in prior systems, the power amplifier draws such heavy current that it causes fluctuations in the potential supplied to the preceding amplifier. This is especially true when voice currents of low frequency are being received. The result is that the power amplifier reacts through the anode filter circuit and causes distortion and rumbling noises in the loud speaker. This difficulty, however, is obviated by having separate filter circuits since filter circuit 57 for supplying the power amplifier cannot cause a potential drop to occur through a relatively high impedance choke 58 of the filter circuit 56. As filter 56 has more resistance than filter 57 the potential across conductors 206 and 207 is considerably less than that across conductors 206 and 209. The positioning of resistances 53 and 54 at a point in the rectifier circuit preceding certain of the filter elements also minimizes the reaction on the grid bias voltage caused by a large increase in the plate current of the amplifier tube.

In Fig. 3 there has been shown a B and C battery eliminator suitable for use with the ordinary radio receiving apparatus and which incorporates certain features of the system described above. In this arrangement the secondary 84 of the transformer 86 is connected to the rectifier element 87. The filaments of these elements are energized from another secondary winding 88. The central tap 89 of secondary winding 84 is connected to the negative plate current conductor 91 through series resistances 92 and 93. The positive plate current conductor 94 is connected to the intermediate point of transformer winding 88. The conductor 96 serves as a positive plate current connection for a power amplifier while conductors 97, 98 and 99, together with conductor 94, serve as sources of different plate current potentials for preceding electron relays. The fil-

ter circuit for the power amplifier includes an inductive choke 115 and shunt capacitance 116, while the other filter includes an inductive choke 117 and capacitance 118. Capacitance 119 may be included in both filter circuits. For supplying reduced potentials to conductors 97, 98 and 99, the conductors 91 and 94 are shunted by an inductive impedance or resistance 120 which is shown as tapped for connections with the conductors 97 and 98. Conductors 91 and 97 may also be shunted by capacitance 121 and conductors 91 and 98 likewise shunted by capacitance 122, in order to minimize interaction between the relays and to further minimize alternating current ripples. Conductor 99 which forms a connection for the plate circuit of the detector, is shown as connected to the intermediate point between the resistance 123 and capacitance 124 which are connected in series and across conductors 91 and 94. The conductor 126 for supplying the grid bias potential for the power amplifier is connected to that end of resistances 92 and 93 which is adjacent to the source of rectified current. Another grid bias conductor 127 is provided for other amplifier relays and is connected between resistances 92 and 93. A shunt capacitance 128 may also be provided to minimize ripples in the negative grid bias. These resistances may be replaced, if desired, by choke coils of suitable characteristics which are made use of as a part of the filter circuit.

In Fig. 4 there is shown a B battery eliminator utilizing the field coil of a loud speaker as one element of the filter circuits. Thus instead of utilizing the choke 118 as in the system of Fig. 3, there is substituted the field coil 131 of the loud speaker. If the inductance of coil 131 together with shunt capacitance 132 is not sufficient to minimize all the ripples, a suitable voltage limiting device such as indicated at 133 may be connected across conductors 91 and 94. The exciting coil 134 of the loud speaker is of course connected in the output circuit of the power amplifier.

I claim:

1. In a signaling system, a plurality of electronic relays connected together in cascade and comprising a high frequency amplifier, a detector and a low frequency amplifier, the low frequency amplifier relay having a grid and plate associated with its input and output circuits; a source of rectified alternating current for energizing said high frequency amplifiers and said output circuit, filter means for minimizing fluctuations in the current supplied from said source, said filter means including reactive elements, an impedance having resistance and capacity in series and a separate resistance in shunt with the negative lead from said source between some of the filter elements and said source, and a

connection between said input circuit and the end of said impedance adjacent said source whereby the grid of said low frequency amplifier is rendered negative.

5 2. In an amplifying system, an electron relay having grid, plate and electron emission elements, an output circuit connected across the plate and electron emission element, an input circuit connected to the grid,
10 a source of direct current for energizing the plate circuit, and a pair of impedance circuits, one including resistance and capacity in series and the other including resistance in shunt therewith connected to effect a potential drop in the negative lead from said source for placing a negative bias upon the grid.

3. In an amplifying system, an electron relay having grid, plate and electron emission elements, an output circuit connected across the plate and electron emission element, an input circuit connected to the grid, a source of direct current for energizing the plate circuit, a filter circuit inserted between
25 the source and the output circuit, an impedance in series with the negative lead from said source for effecting a potential drop, said impedance forming a part of the filter circuit and comprising a pair of resistors connected
30 in parallel through a condenser, and means for impressing said potential drop upon the grid to bias the grid negatively with respect to the electron emission element.

In testimony whereof, I have hereunto set
35 my hand.

GEORGE T. ROYDEN.
